TEMPERATURE TESTING CHAMBER

Leslie A. Brewster, Dayton, Ohio

Application June 30, 1944, Serial No. 542,997

3 Claims. (Cl. 257—9)

(Granted under the act of March 3, 1883, as
amended April 30, 1928; 370 O. G. 757)

1

The invention described herein may be manufactured and used by or for the Government for governmental purposes, without the payment to me of any royalty thereon.

The invention to be hereinafter described relates to air mixer for heat testing cabinets.

It has long been common practice to test the effects of varying degrees of temperature or heat upon given material, manufactured articles, equipment, etc. For this purpose, heat testing cabinets have been devised of various constructions. Frequently the cabinet comprises several intercommunicating compartments or chambers, a circulating device for causing air flow through such compartments and a control device for proportioning or otherwise regulating the air flow through the compartments. Some such cabinets also include an air heater and an automatic regulator for the heater. Many of these cabinets, as heretofore constructed, are unnecessarily complicated, correspondingly expensive and proportionately inefficient. Many of them flow a current of warm air directly on the coolant to lower the air temperature. The result of that is a great waste of the coolant and too sudden drop in the temperature of the heated air, making regulation difficult. Also sudden variations in temperature may be damaging to the materials being tested. Such sudden changes are very likely to be damaging to the test cabinets. Even when there is not that damaging effect to the materials being tested, the relatively sudden changes in temperature resulting make control difficult and may cause uncertain, inaccurate and unreliable calculations and determinations so that the tests are of less value than they should be.

The present invention avoids the above and other objections and provides a simple, efficient, compact and low cost testing cabinet of few parts in which the air flow control is simple and efficient and no hot air current is permitted directly over and across the coolant.

In order to more clearly disclose the construction, operation and use of the invention reference should be had to the accompanying drawings forming part of the present application.

Throughout the several figures of the drawings like reference characters designate the same parts in the different views.

In the drawings:

Fig. 1 is a front view of the cabinet, closed;

Fig. 2 is a horizontal cross section on line 2—2 of Fig. 3; and

Fig. 3 is a central vertical cross section.

A preferred construction comprises a box like

2

cabinet body 1 adequately heat insulated relatively to the uses to which it is to be put. This body is divided into three intercommunicating chambers 2, 3 and 4 respectively.

Chamber 2 is the cold chamber in which is placed a coolant such as Dry Ice. Any other suitable coolant, refrigerant or refrigerating device may be used, adequate for the purposes for which the cabinet is to be used. Any such material or device should be, and logically is, disposed in the upper part of the chamber, a shelf, bracket or similar support 5 on one wall of the chamber providing a seat in extension of the top wall of the hot air chamber 3. In this arrangement, the Dry Ice or other cooling agent bridges the space between 5 and the top of the horizontal branch of 3. Preferably a heavy screen, grid, or other open-work plate or like device not here shown or further described, bridges the space immediately below the cooling means and acts as additional support. This is particularly desirable where ice or Dry Ice is used. As such coolants decrease in size they would eventually drop through between 5 and the end of chamber 3 into the lower part of chamber 2 where they would be of least efficiency. Such a grid is, therefore, desirable but not an essential part of this application.

In the lower part of chamber 2 below the refrigerant or cooling means and below the hot air chamber 3 is journaled a fan extending into an opening in the lower part of wall 7 which separates chambers 2 and 4.

The hot air chamber 3 between chambers 2 and 4, in the preferred form of the invention, is substantially L-shaped in vertical cross section, the lower outer end of the L opening into the upper part of the lower portion of the cold chamber 2 directly beneath the support for the cooling or refrigerating means. This chamber 3 comprises the two parallel, spaced, L-shaped partition walls 8 and 9 extending from front to rear of the cabinet, those cabinet wall portions between 8 and 9 completing that chamber. Or, of course, chamber 3 may be made as a complete unit with end walls and insertable as one piece. Walls 8 and 9 are provided with circulation openings 10 and 11, respectively, for the flow of test chamber air from chamber 4 simultaneously into 3 and 2, exclusively into 2 or exclusively into 3, according to circumstances and as desired. Openings 10 and 11, preferably, extend the full length of walls 8 and 9, from front to rear of the cabinet. However, such openings may or may not be continuous throughout their lengths as may be individ-

ually desired. In the cabinets so far actually constructed, they are continuous. As shown, in the preferred construction, openings 10 and 11 are aligned. Between openings 10 and 11, in 3, is journaled, either in the end walls of 3 or in the walls of the cabinet, a cylindrical valve 12 so proportioned that it may completely close either opening 10 or 11 or the upper portion of chamber 3.

The normal position of 12 is as shown in the cross sectional view. In that position, air circulated by fan 6 through chamber 4 passes through opening 10 in wall 3 and into chamber 3. Due to the position of valve 12, part of the flow will pass downwardly in chamber 3 and the remainder will pass into the upper part of the cold chamber 2 above, and down over the dry ice or other coolant or refrigerating medium or device, and thence into the lower part of chamber 2 for recirculation by fan 6. And, as will be clear, the air passing down in chamber 3 will also flow into the lower part of chamber 2, the two flows mixing as they are fed forward by fan 6 into chamber 4.

Within chamber 3 and in the downward path of flow therethrough is a suitable resistance heater 13 of well known type.

Within chamber 4 is a well known type of standard thermostatic heat control device 14. It is connected in usual and well known manner in the circuit of heater 13 to automatically turn on or off the heating current. These devices and their connections and interconnections are all well known to those skilled in the art and need no further illustration or description here.

The axis or shaft 15 of valve 12 is extended through the front wall of the cabinet and provided with a pointer or other device 16 cooperating with a suitable dial plate 17. Valve 12, in originally assembling the cabinet, is so set that its relative control positions will be indicated on the dial by the pointer, the pointer also constituting a handle for manipulating the valve. For instance, in the present construction, the dial could readily show cold, hot, intermediate and closed. And, of course, it may be readily graduated to indicate fractional or small movements in one direction or the other. In that arrangement, cold could indicate that valve 12 would be set to direct either all air flow through 10 and 11 and the cold chamber 2 and none through heating chamber 3 or a considerably greater part through 10 and 11 and 2 than through 3. In the same arrangement, hot could indicate, similarly, a position of valve 12 directing all or most of the flow through chamber 3. In like manner, intermediate could indicate a valve position directing approximately equal portions of the air from chamber 4 through 3 and 2. This position is illustrated in Fig. 3. Finally, closed could indicate a valve position completely closing 10 and cutting off chamber 4 from 2 and 3, permitting opening of chamber 2 for renewing refrigerant or replacing, repairing, etc. the refrigerating device. In that case, the temperature in the testing chamber 4 will not be appreciably affected during opening of chamber 2.

The operation of the invention is as follows:

Set the thermostat 14 at the temperature desired for the testing chamber 4 and start fan 6. Then place the desired coolant or refrigerating device in chamber 2 and close the cabinet doors. Manipulate valve 12 until the thermostat 14 shows the temperature in 4 being maintained constant. When that point is reached, place in

the test chamber the material or article to be tested and leave it the predetermined period of the test.

The thermostat and valve, as set, will maintain the temperature constant.

By this construction and arrangement hot air from chamber 3 never flows directly onto the coolant or refrigerator or through the cold chamber 2. The only air that flows into that chamber 10 is from the test chamber which is considerably lower in temperature.

By this construction and arrangement neither the hot air from chamber 3 nor the cold air from chamber 2 goes directly into the test chamber 15 4. Instead both are intimately mixed by fan 6 and delivered as a mixture with temperature intermediate between that of the two and approximately that of the test chamber. This gives a 20 far more uniform condition in chamber 4 and avoids possible sharp drops or rises in temperature in that chamber.

It is thought that the construction, operation and use of the invention will be clear from the preceding detailed description.

25 Many changes may be made in the construction, arrangement and disposition of the various parts of the invention and in the materials used therein, within the scope of the appended claims without in any way departing from the field of the invention and it is meant to include all such within this application wherein only one preferred form has been disclosed by way of illustration and with no thought or intention to, in any degree, limit the invention thereby.

35 Having thus described my invention, what I claim and desire to protect by Letters Patent is:

1. A testing cabinet comprising, in combination, a testing chamber, a cooling chamber, a heating chamber extending from the front through to the rear of said cabinet between said testing and cooling chambers, said heating chamber being provided with aligned openings for the flow of air from said testing chamber into said heating chamber and across said heating chamber into said cooling chamber, means for circulating air from said heating and cooling chambers into said testing chamber, and unitary valve means having a plurality of positions for regulating said air flow from said testing chamber, said valve means being selectively and progressively variable from a first position in which all the air flowing from said testing chamber is cut-off, to a second position in which all the air flows from said testing chamber into said cooling chamber, to a third position in which all the air flows from said testing chamber into said heating chamber, said valve means being variably positionable between the aforementioned positions for proportioning the flow of air from said testing chamber within the limits set by the aforesaid positions.

2. A testing cabinet comprising, in combination, a testing chamber, a cooling chamber, a heating chamber extending from the front through to the rear of said cabinet between said testing and cooling chambers, said heating chamber being provided with aligned openings for the flow of air from said testing chamber into said heating chamber and across said heating chamber into said cooling chamber, said heating chamber opening into the lower portion of said cooling chamber, said testing chamber having an opening for receiving the combined output of said heating and cooling chambers, means positioned 65 in said testing chamber opening for circulating

the air from said heating and cooling chambers into said testing chamber, and unitary valve means having a plurality of positions for regulating the air flow from said testing chamber, said valve means being selectively and progressively variable from a first position in which all the air flowing from said testing chamber is cut-off, to a second position in which all the air flows from said testing chamber into said cooling chamber, to a third position in which all the air flows from said testing chamber into said heating chamber, said valve means being variably positionable between the aforesaid positions for proportioning the flow of air from said testing chamber within the limits set by the aforesaid positions.

3. A testing cabinet comprising, in combination, a testing chamber, a cooling chamber, a heating chamber extending from the front through to the rear of said cabinet between said testing and cooling chambers, said heating chamber being provided with aligned openings for the flow of air from said testing chamber into said heating chamber and across said heating chamber into said cooling chamber, said testing chamber having an opening for receiving the combined output of said heating and cooling chambers, means positioned in said testing chamber opening for circulating the air from said heating and cooling chambers into said testing chamber, 30 means within said cooling chamber positioned

above the opening into said testing chamber for supporting a cooling medium, and unitary valve means having a plurality of positions for regulating the air flow from said testing chamber, said valve means being selectively and progressively variable from a first position in which all the air flowing from said testing chamber is cut-off, to a second position in which all the air flows from said testing chamber into said cooling chamber, to a third position in which all the air flows from said testing chamber into said heating chamber, said valve means being variably positionable between the aforesaid positions for proportioning the flow of air from said testing chamber within the limits set by the aforesaid positions.
